UNITED STATES PATENT OFFICE.

EMILE A. LAURENT, OF DENVER, COLORADO.

DESIGN FOR A LAMP.

53,306.

Specification for Design. Patented May 13, 1919.

Application filed May 6, 1918. Serial No. 232,956. Term of patent 14 years.

To all whom it may concern:

Be it known that I, EMILE A. LAURENT, citizen of the United States, residing at Denver, in the county of Denver and State of Colorado, have invented a new, original, and ornamental Design for a Lamp, as shown in the accompanying drawing.

The figure is an elevation view of a lamp, showing my new design therefor.

I claim:

The ornamental design for a lamp as shown.

EMILE A. LAURENT.
